US00D991637S

(12) **United States Design Patent** (10) Patent No.: **US D991,637 S**
(45) Date of Patent: **** Jul. 11, 2023**

(54) **SNEAKER**

(71) Applicant: **ROTHY'S, INC.**, San Francisco, CA (US)

(72) Inventors: **La Vion Gibson**, San Francisco, CA (US); **William Roth Martin**, San Francisco, CA (US)

(73) Assignee: **ROTHY'S, INC.**, San Francisco, CA (US)

(**) Term: **15 Years**

(21) Appl. No.: **29/740,617**

(22) Filed: **Jul. 6, 2020**

(51) LOC (14) Cl. **02-04**

(52) U.S. Cl.

USPC **D2/969**; D2/907

(58) Field of Classification Search

USPC D2/902-908, 909, 947, 951, 953, 960, D2/969, 973

Primary Examiner — Leanne Was-Englehart

Assistant Examiner — Yelizaveta Y Masalimova

(74) Attorney, Agent, or Firm — ArentFox Schiff LLP

(57) **CLAIM**

The ornamental design for a sneaker, as shown and described.

DESCRIPTION

FIG. 1 is a rear right perspective view of an embodiment of a sneaker showing our new design;

FIG. 2 is front view of the design shown in FIG. 1;

FIG. 3 is a rear view of the design shown in FIG. 1;

FIG. 4 is a right side view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

The broken lines and the white areas within the broken lines as shown in the figures are included for the purpose of illustrating portions of the sneaker that form no part of the claimed design.

1 Claim, 7 Drawing Sheets
